UNITED STATES PATENT OFFICE.

GASTON A. GUYOT, OF ATTLEBORO, MASSACHUSETTS, ASSIGNOR TO GUYOT BROTHERS COMPANY INC., OF ATTLEBORO, MASSACHUSETTS.

GUARD FOR PUNCH PRESSES.

Application filed December 24, 1926. Serial No. 156,899.

This invention relates to certain new and useful improvements in guards for punch presses, and relates more particularly to a guard which automatically acts to brush the hand of the operator out of the space between the plunger and the die upon downward movement of the former, thereby moving the hands of the operator out of the danger zone and accordingly out of the path of the descending plunger.

The primary object of the present invention is to provide a device of this type which is of simple and economical construction, which involves a minimum of parts and which also provides a compact assemblage of the parts and further one wherein the parts are relatively small and occupy but little space.

Further, the invention aims to provide a device of this type which is positive and effective in its action and which can be easily and quickly adjusted so as to vary the relation between the hand engaging element and the bed or die of the press.

The invention has still further and other objects which will be later herein set forth and manifested in the course of the following description.

In the drawings:

Fig. 1 is a front elevation of the invention applied to a punch press of conventional form;

Fig. 2 is a side elevation;

Fig. 3 is a rear elevation;

Fig. 4 is a section on line 4—4 of Fig. 3, and

Fig. 5 is a sectional elevation of the guard supporting post.

The press depicted in the drawings is of conventional form and includes a frame 1 having a base 2 upon which latter is disposed a bed or die 3, the latter underlying the usual plunger 4 that is carried by the head 17 which latter is vertically reciprocated by means of the crank 5 on the shaft 6 driven by wheel 7. It will be understood however, that the invention can be applied to other forms of presses, and in proceeding in accordance with the present invention, a post or column 8 is secured to the base 2 and is provided with a turnable head 9 that may be adjusted by means of a wrench and the wrench holes 10, and which head is held in adjusted position by the lock nuts 11. An arm 12 is pivoted to the post 8 so as to move

in a true horizontal plane and has its forward end 13 preferably offset and curved so as to engage the hand of the operator and brush or wipe the latter out of the danger zone.

As shown in Fig. 5, the movable arm 12 is journalled upon a hub 9^a forming part of the piece 9. The hub is of such weight as to permit the arm 12 to move freely when actuated. A washer 9^b is placed on top of this hub so as to hold the arm in position and the jam nuts 11—11 are then moved to lock the washer. Below the part 9 are placed a pair of jam nuts 10 and 10^a. The post 8 is secured to the base 2 by a downwardly extending bolt 8^a or other suitable means. By loosening the jam nuts 11—11 the member 9 can be screwed up to the desired position and the nuts 10 and 10^a are then moved to engage the lower face of member 9 to retain the same in its adjusted position.

The arm 12 is pivoted intermediate its ends and the rear end or tail 14 thereof is connected to a coil spring 15 which latter is in turn connected to the frame 1, so that the end 13 of the arm 12 normally occupies the dotted line position of Fig. 4, and wherein it will be noted that such end overlies the bed or die 3.

A cam plate 16 is secured to the reciprocating head 17 of the press, which head carries the punch 4. The cam 16 is formed with an elongated slot 18 through which screws 19' are extended and secured to the head 17 so as to thereby enable adjustment of the cam 16 as may be found desired or necessary. As shown in Fig. 2 of the drawings, the cam 16 is of somewhat Z-shape and has its effective portion disposed in a vertical plane and beveled as indicated at 19.

In operation upon downward movement of the head 17 and therewith the punch 4, it will be seen that the inclined edge 19 of the cam will engage the tail 14 of the arm 12 and swing or move the latter from the dotted line position of Fig. 4 to the full line position, so that should the hand of the operator be in the danger zone or otherwise stated, between the bed or die 3 and the downwardly moving punch 4, the hand will be brushed or moved out of the danger zone and accordingly from beneath the downcoming punch 4.

From the foregoing, it will be noted that

but a single straight, pivoted arm is employed and which is mounted on and at one side of the base of the press and projects but slightly thereabove, so that the press is left substantially free of interfering parts.

Having thus described my invention what I claim as new and desire to secure by Letters Patent is:

1. In a press guard, a post formed for 10 securingment to the base of a press, an arm pivoted intermediate its ends to the post, means to effect vertical adjustment of the arm so as to vary the space between same and the base, a spring connected to the rear 15 end of the arm and formed for attachment to the press frame so as to normally dispose the front of the arm over the die of the press, and a substantially Z-shaped cam having means to attach same to the reciprocating 20 head of the press, said cam having its lower end formed with a vertical part having an inclined edge engageable with the rear end of the arm.

2. In a press guard, a post formed for 25 securingment to the base of a press, an arm pivoted intermediate its ends to the post, means to effect vertical adjustment of the arm so as to vary the space between the same and the base, a spring connected to the rear 30 end of the arm and formed for attachment to the press frame so as to normally dispose the front of the arm over the die of the press, and a cam formed for attachment to the reciprocating head of the press and engageable with the rear end of the arm.

3. In a press guard, a guard, means to pivot the guard for horizontal movement between its ends to the base of the press, means to tension the guard, and means operable by the reciprocating head of the press 40 and engageable with the rear end of the

guard for moving the front end thereof over the base.

4. In a press guard, a guard, means to mount the guard between its ends for swinging movement in a horizontal plane, and a cam on the reciprocable head of the press and engageable with the tail of the guard to operate same.

5. In a press guard, a substantially horizontal guard, means between the ends of the guard to pivotally mount the guard for horizontal rotational movement, said means being spaced from the front end of the guard so as to leave said end free for engagement with the hand of the operator, means to tension the guard connected to the rear end thereof, and means engageable with said rear end of the guard to actuate the latter from a moving part of the press.

6. In a press guard, a substantially horizontal guard, means between the ends of the guard to pivotally mount the guard for horizontal rotational movement, said means being spaced from the front end of the guard so as to leave said end free for engagement with the hand of the operator, and means operable by a moving part of the press and engageable with the rear end of the guard to actuate the latter.

7. In a press guard, a base, a post secured to said base, an arm pivoted to said post, means carried by the post to effect vertical adjustment of the arm with respect to the base, and means carried by the reciprocating head of a press and engageable with said arm to effect movement of the arm in a horizontal plane over the base.

In testimony whereof I have hereunto signed my name to this specification.

GASTON A. GUYOT.
